UNITED STATES PATENT OFFICE.

LAURIE H. THALMAN, OF SAN DIEGO, CALIFORNIA.

ACETYLENE-GAS GENERATOR.

1,241,680.

Specification of Letters Patent.

Patented Oct. 2, 1917.

Application filed September 2, 1915, Serial No. 48,682. Renewed June 22, 1917. Serial No. 176,425.

To all whom it may concern:

Be it known that I, LAURIE H. THALMAN, a citizen of the United States, residing at San Diego, in the county of San Diego and 5 State of California, have invented certain new and useful Improvements in Acetylene-Gas Generators, of which the following is a specification.

This invention relates to acetylene gas 10 generators, and it has for its object the provision of a simple and inexpensive structure arranged in such manner that the proper amount of carbid necessary to maintain the proper gas pressure, will be automatically 15 fed into the water.

It is desirable in devices of this nature to maintain the bulk of the carbid out of contact with the water, because, where the water is fed into the entire bulk of carbid more gas 20 is generated than is desirable, and the entire body of carbid is rendered useless.

I am aware of the fact that generators 25 have been devised in which the carbid is fed into the water, but this has usually been accomplished by the employment of more or less complicated and expensive structures. It is, therefore, a particular object of the present invention to provide a simple and inexpensive structure in which the feeding 30 of the carbid is controlled by a float, this float being forced downwardly in a body of water by the gas pressure when the desired amount of gas has been generated.

Further objects and advantages of the invention 35 will be set forth in the detailed description which now follows.

The figure shown in the accompanying drawing is a vertical sectional view of a gas 40 generator constructed in accordance with the invention.

Referring to the drawing, 5 designates a main tank, and 6 a carbid receptacle, the latter being provided with a filling cap 7. A sleeve 8 is disposed vertically in the carbid receptacle 6 and this sleeve is provided 45 at its lower end with a guard apron 9 which holds most of the weight of carbid from the valve 12 and limits the amount of carbid which may feed downwardly to a port 10, through which communication is established 50 between the interior of receptacle 6, and the interior of tank 5. A valve stem 11 passes through sleeve 6 and carries a valve 12. This stem is provided at its upper end with

a handle 13, and a packing nut 14 prevents leakage of gas about the valve stem 13. When the carbid receptacle 6 is being filled with carbid the valve 12 is lowered to close port 10, and this valve is also lowered when it is desired to stop further generation of gas, but when the device is in operation this valve 12 is lifted to lie within the apron 9, and then the passage of carbid through port 10 is controlled by a second valve 15 mounted upon one end of a lever 16. This lever is pivoted at 17 to an ear 18 of tank 5. This lever passes through an opening 19 formed in the wall of a float tank 20 and is pivoted at 21, to an ear 22 of an inverted, cup like float 23. This float is provided 70 with a guide sleeve 24 which it fits over a guide pin 25. The tank 20 is provided with a filling cap 26. The tank 5 is provided with a pet cock 27, and with a gas discharge pipe 28.

The operation of the device is as follows:—

Filling plug 26 is removed, and water is poured into tank 20 and overflows through opening 19 into tank 5 until it rises to the stop cock 27 whereupon this stop cock is closed and filling plug 26 is put in place. If the valve 12 be now lifted carbid will flow into the water contained in tank 5 and thereby generates gas. The pressure of the gas so generated acts upon the water contained within the float tank 20 and also upon the upper surface of the float with the result that such a reduction of the volume of air within the float follows as to permit a lowering of the water level with a consequent sinking of the float. The result of this is that valve 15 is moved upward to close opening 10. When sufficient gas has been taken off through pipe 28 to reduce the pressure, it is apparent that this operation will be repeated and that this operation will continue to be repeated until either the carbid is exhausted, or the valve 12 is forced downwardly to stop further feed of the carbid. A drain plug 29 is located near the bottom of the tank, and an agitator 30 is mounted upon a shaft 31 and is arranged to be rotated by gearing 32 and handle 33, by virtue of which construction it is possible to thoroughly clean tank 5.

It is to be understood that the invention is not limited to the precise construction set

forth, but that it includes within its purview such changes as come within the spirit of the appended claims.

Having described my invention, what I claim is:—

- 5 1. In a device of the character described, the combination with a main tank, of a carbid receptacle mounted upon the top thereof and having an opening formed in its bottom through which the carbid is discharged into the main tank, a float tank supported from the top of the main tank and depending into said main tank, said float tank being provided with an overflow opening which 10 discharges into the first named tank, a float of inverted cup shape disposed within the float tank, a lever pivoted intermediate its ends and pivoted at one of its ends to said float, a valve carried by the upper end of 15 said lever and arranged to close the opening formed in the bottom of said carbid receptacle, said float tank being materially smaller than the main tank, the gas pressure generated in the main tank passing through the 20 overflow opening and acting upon the surface of the water contained within the float tank to cause a compression of the air within the float and a consequent lowering of the 25 water level and the float to thereby close the 30 valve.

2. In a device of the character described the combination with a main tank, closed

at the bottom and a carbid receptacle in communication therewith, a pivoted lever, a valve carried by said lever arranged to 35 control the passage of carbid from said carbid receptacle to said tank, a float of inverted cup form to which said lever is pivoted, a float tank in which said float is disposed, said float tank being provided with 40 an overflow opening for discharging into the first named tank, and a filling means in the top of the float tank.

3. In a device of the character described the combination with a main tank, a carbid 45 receptacle in communication therewith, a pivoted lever, a valve carried by said lever arranged to control the passage of carbid from said carbid receptacle to said tank, a float of inverted cup form to which said 50 lever is pivoted, a float tank in which said float is disposed, said float tank being provided with an overflow opening for discharging into the first named tank, a filling 55 means in the top of the float tank, and a manually operable valve for cutting off communication between the carbid receptacle and the first named tank.

In testimony whereof I affix my signature in presence of two witnesses.

LAURIE H. THALMAN.
